FIG. 7.

UNITED STATES PATENT OFFICE

2,460,438

GARMENT HANGER

Morris Treiman, Los Angeles, Calif., assignor to
 Allied Plastics Company, Los Angeles, Calif.,
 a copartnership

Application December 13, 1947, Serial No. 791,637

6 Claims. (Cl. 223—92)

1

The present invention relates to garment hangers, and its primary object is to provide a new and improved form of swiveled hook hanger having a body which can be molded of plastic or the like in a simple, two-piece die, and in which the hole for receiving the shank of the wire hook is molded into the body without requiring the use of complicated and expensive retractile cores.

One of the principal obstacles retarding the manufacture of swiveled hook plastic coat hangers has been in the formation of a hole in the body for reception of the shank of the wire hook. Heretofore, it has been necessary either to mold the plastic hanger body without a hole, and then drill the hole, which is an expensive and time-consuming operation that is probably responsible for about half the cost of the finished article; or else to use complicated and expensive dies employing retractile cores.

The present invention overcomes these difficulties by providing a novel arrangement whereby the hole for the shank of the hook is formed by a plurality of vertically aligned slots or cavities which extend into the hanger body alternately from opposite sides thereof, each of said slots overlapping and intersecting the ends of the adjoining slots so that the overlapping portions form a continuous vertical hole extending down into the body from the top edge thereof. Thus, the hole is formed by a series of oppositely facing, open-sided cavities which co-operate to confine the shank of the hook from all sides, yet these cavities can be formed by simple projections or lugs on the male and female dies, and no retractile cores are required. By eliminating both the drilling operation and the need for complicated dies, the present invention makes it possible to produce a swiveled hook, plastic coat hanger at a cost comparable to that of wooden hangers.

Another object of the invention, therefore, is to provide a swiveled hook, plastic coat hanger which is inexpensive and simple to manufacture, and which is also attractive in appearance, as well as rugged in construction.

Other objects and advantages of the invention will become apparent to those skilled in the art upon consideration of the following detailed description of the preferred embodiment thereof, reference being had to the accompanying drawings, in which:

Figure 1 is a perspective view of a garment hanger embodying the principles of the invention;

Figure 2 is an enlarged side elevational view of the same;

Figure 3 is a still further enlarged sectional view taken along the line 3—3 in Figure 2;

Figure 4 is a sectional view taken at 4—4 in Figure 2;

Figure 5 is a section taken at 5—5 in Figure 2;

Figure 6 is a section taken at 6—6 in Figure 2; and

Figure 7 is a section taken at 7—7 in Figure 2.

10 In the drawings, the hanger of the invention is designated in its entirety by the reference numeral 19, and comprises a body 11, to which a hook 12 is swivel-connected. The body 11 is a shoulder-contoured, horizontally elongated injection molding of any suitable plastic material, and is generally of I-beam section, being formed with a relatively thin vertical web 13, and having a rounded flange 14 extending around its outer edge. A vertically disposed enlargement 15 of substantially cylindrical cross-section is formed in the web 13 between the top and bottom flanges at the mid-point of the hanger, and this enlargement is divided at a point slightly above its mid-point by a generally rectangular 20 through slot or aperture 16 which extends through the web of the body 11 from one side thereof to the other.

Extending into the enlargement 15 alternately from opposite sides of the hanger are vertically aligned slots, or cavities 20, 21, 22 and 23 each of which reaches inwardly beyond the center plane of the hanger, and has a cylindrically curved inner portion or bottom 24, the center of curvature of which is on the axis of the enlargement 15. The adjacent ends of the adjoining slots 20 and 21 in the top section of the enlargement 15, and of the slots 22 and 23 in the bottom section thereof, overlap and intersect with one another, so that the bottoms or inner portions of the cavities are connected, i. e., open into one another, to form an open passage. Each of the two center slots 21 and 22 opens at one end into the rectangular through slot or aperture 16, while the top slot 20 extends up into the flange 14 and is open at its end from the top edge of the hanger. Thus, the passage formed by the interconnected bottoms of the overlapping slots, extends down from the top edge of the hanger to the lower edge of the bottom slot 23; and being made up of opposed semi-cylindrical surfaces, the passage is seen as a cylindrical hole when viewed along its axis.

The hook 12 is made of heavy gage wire and is formed with a straight shank portion 30 which is adapted to be inserted down into the hole formed by the interconnected slots. In assembling the hanger, the shank 30 is passed

through the hole in a washer 31 disposed with-in the through slot 16, and after the shank has been inserted to the full depth of its hole, ears 33 are staked out from the shank 30 below the washer 31. These ears serve as locking pro-jections, and engage the underside of the washer to prevent the shank from being pulled out of the hanger body 11. The purpose of the through slot or aperture 16, thus, is to provide space for the washer 31, and also to provide an opening to enable staking tools to get at the shank 30.

With the hanger thus assembled, it will be seen that the hook 12 is free to rotate with re-spect to the hanger body 11, yet is prevented by the washer 31 and ears 33 from being pulled out of its opening. Inasmuch as the hole for recep-tion of the shank of the hook 12 is formed merely by a series of interconnected, open slots which can be formed easily by using projecting lugs on the male and female dies in which the hanger body is molded, there is no need for using re-tractible cores which complicate the die con-struction and greatly increase the cost thereof.

While I have shown and particularly described a plastic coat hanger in which the hole formed by the aligned, oppositely facing slots is for the re-cption of the shank of a swiveled supporting hook, it will be appreciated that the same prin-ciple might be utilized with equal advantage to form holes for elements other than hooks. For example, horizontally extending holes might be formed in both ends of the hanger body to re-cieve a horizontal rod or bar upon which trousers or slacks may be supported. Various other changes may be made in the shape and arrange-ment of the several parts without departing from the scope of the claims appended hereto.

I claim:

1. A garment hanger comprising a body, a ver-tically disposed series of slots extending into said body alternately from opposite sides thereof, each of said slots having an inner portion overlapping the inner portion of the next adjacent slot, all in such manner that said overlapping inner por-tions cooperate to define the cross section of a vertical hole extending down into said body from the top edge thereof and opening alternately on opposite sides, a hook having a shank extending down into said hole, said body having an open-ing extending through from one side to the other and intersecting said hole, a washer mounted on said shank within said opening and adapted to bear on the top edge thereof, and means for se-curing said washer to said shank, whereby the lat-ter is prevented from pulling out of said hole.

2. A garment hanger comprising an elongated body having a relatively thin web with a flange extending around the edges thereof, a vertically disposed enlargement formed on said web at the midpoint of said body, a vertically disposed se-ries of round-bottomed slots extending into said enlargement alternately from opposite sides thereof, each of said slots overlapping laterally to define the cross section of a cylindrical ver-tical hole extending down into said body through said enlargement from the top edge of said body, a hook having a shank extending down into said hole, said body having an opening extending through from one side to the other and intersecting said hole, and a washer mounted on said shank within said opening and adapted to bear on the top edge thereof, said shank having pro-jections formed thereon below said washer to en-gage the latter and prevent the shank from pull-ing out of said hole.

3. A garment hanger comprising a hanger body having opposite sides and a top edge, a vertically disposed series of end-adjoining slots extending laterally into said body from the sides thereof, said series of slots beginning at the top edge of said body and extending without interruption downwardly into said body to a predetermined depth, at least two of said slots being sunk into said body from one side thereof and being separated by at least one intervening slot sunk into said body from the opposite side thereof, said two slots and said intervening slot having over-lapping inner portions cooperating to define the cross-section of a hook-shank-socket.

15 4. A garment hanger comprising a hanger body having opposite sides and a top edge, a vertically disposed series of end-adjoining slots extending laterally into said body from the sides thereof, said series of slots beginning at the top edge of said body and extending without interruption downwardly into said body to a predetermined depth, at least two of said slots being sunk into said body from one side thereof and being separated by at least one intervening slot sunk into said body from the opposite side thereof, said two slots and said intervening slot having over-lapping inner portions cooperating to define the cross-section of a hook-shank-socket, a hook hav-ing a shank portion extending downwardly through said socket, and means on said shank portion engageable with said body at the inner end of one of said slots so as to prevent with-drawal of said shank from said socket.

30 5. A garment hanger comprising a hanger body having opposite sides and a top edge, two end-adjoining slots sunk laterally into the sides of said body alternately from opposite sides there-of, the first of said slots opening through the top edge of said body, said slots having inner por-tions laterally overlapping and opening into one another, said body having immediately at the bot-tom edge of the lowermost of said slots, and open-ing thereinto, an aperture extending through the body from side to side, and an additional slot 35 sunk laterally into said body below said aperture from the same side thereof as the uppermost of the aforementioned slots, said additional slot open-ing at the top edge thereof into said aperture, an inner portion of said additional slot being vertically aligned with and overlapping said overlapping inner portions of the aforementioned slots, a hook having a shank extending through the overlapping portions of said slots and through said aperture, and means on said hook shank 40 within said aperture engageable with the body to prevent withdrawal of said shank from said body.

45 6. The method of molding a relatively flat gar-ment hanger body with a hole extending into the body from one edge thereof, that includes: form-ing the sides of said body during the molding thereof with a plurality of end-adjoining slots extending laterally into the body alternately from opposite sides thereof and to depths such that the inner portions of the slots extending from opposite sides of the body overlap and open into one another.
